UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S SKIRT.

SPECIFICATION forming part of Design No. 14,918, dated March 25, 1884.

Application filed January 23, 1884. Term of patent 3½ years.

To all whom it may concern:

Be it known that I, CATHERINE O'HARA, of the city, county, and State of New York, have invented and produced a new and original Design for a Pattern of a Lady's Walking-Skirt, (numbered 9,063;) and I do hereby declare that the engraved prints accompanying this specification convey to any one accustomed to using paper patterns a clear understanding of how a garment made up by the pattern will appear.

The design shows a walking-skirt, displaying long narrow panels flaring from the center of the front, and overlapped at their back edges

by wide side draperies, and also displaying a deep full back-drapery that exhibits three draping-plaits in each front edge and loopings at its center.

What I claim as my invention, and desire to secure by Letters Patent, is—

The design for a lady's walking-skirt, as shown in the engraved prints accompanying this specification.

CATHERINE O'HARA.
